JAMES EMERSON, OF WILLIMANSETT, MASSACHUSETTS.

STEAM-VALVE CONNECTION FOR RAILWAY-CARS.

SPECIFICATION forming part of Letters Patent No. 314,007, dated March 17, 1895.

Application filed May 7, 1894. (No model.)

To all whom it may concern:

Be it known that I, JAMES EMERSON, a citizen of the United States, residing at Willimansett, in the county of Hampden and State of Massachusetts, have invented new and useful Improvements in Steam-Valve Connections for Railway-Cars, of which the following is a specification.

This invention relates to improvements in automatically-operating steam-valves for connecting steam-pipes between railway-cars, the object being to provide improved self coupling and disconnecting valve devices to be attached to the ends of pipes between cars, which, when brought together by the movement of the latter, become properly connected, and as a result of such connection have their steam-valves opened to allow steam to flow through them, and which, when drawn apart by the separation of the cars, operate to close the valve openings, so that steam will not escape from the pipes within either car.

In the drawings, forming part of this specification, Figure 1 is a side elevation, partly in section, of self connecting and disconnecting valve devices embodying my invention, and in which are shown parts of the devices by which they are secured to the cars. Fig. 2 is a longitudinal section. Fig. 3 is a detail view. Figs. 4 and 5 are respectively plan and side views of the said devices for securing the valve parts to the cars, and showing a portion of the said parts.

In the drawings, (see Fig. 5,) *w w* indicate portions of the bottom and end of a car. To the bottom of the latter a plate, *v*, is bolted having a pivot-bolt, 15, in its end. To said bolt 15 the rod 16 is pivoted, running in a horizontal direction toward the end of the car, 40 and its free end turns down forming the arm 15, on the end of which is formed the sleeve 14. A yoke, *w²*, of rectangular form is bolted by an arm, *z*, thereon to the end of the car. A spring-bar, 17, is bolted on each side of 45 the rod 16, the free ends of which pass through the yoke *w²*, and springing outwardly bear against the opposite sides of said yoke, and thus the latter, through said spring-bars, offers a certain resistance to any lateral vibration 50 of the rod 16 and arm 15, and serves to steady such movements; also, the bars 17 rest on the bottom of yoke *w²* and

support the end of rod 16. A screw-threaded rod, *i²*, passes through sleeve 14 on arm 15, and is adjusted to and secured in different 55 positions longitudinally by the nuts 13. An arm, *h'*, is formed on the end of rod *i'* at right angles to the latter, on the end of which is a yoke-frame surrounding and supporting the yoke 8. (See Fig. 1.)

A set of the above-described valve-supporting devices is applied to each end of the cars, and they are connected with the valve parts, as hereinafter set forth.

The end of one car is provided with a receiving-connection, and the end of an adjoining car has an entering connection secured thereto. The said two connections are shown in Figs. 1 and 2 locked together, and in a position to allow steam to pass through them, 70 and they are adapted to operate in connection with steam-heating pipes in the cars, which are supplied with steam under more or less pressure from the engine or from other sources.

The said receiving-connection is constructed 75 with a large open mouth, *A*, having a tubular extension, *y*, to which is screw-connected, as shown, a back-pressure-valve case, *C*. Between the inner end of said case and a shoulder around the interior of the part *y* is 80 placed a series of elastic packing-rings, *F*, having metallic rings between them, as shown. The inner edges of said elastic rings project into the passage in the tubular part *y*, into which the valve-case *m* is forced, as herein- 85 after described. A back-pressure valve, *D*, having a spindle, *e*, thereon, is supported in case *C* by a perforated disk, *f*, which has a hub through which spindle *e* passes, said valve being adapted to seat itself against the 90 shoulder *s* in case *C*, and to be moved from its seat by the said entering connection, as shown in Fig. 2. A spring, *B*, is bolted by one end to the part *y* and extends into a slot 95 in the mouth *A*, having its free end provided with a handle, 21, reaching above the said slot, two reversely-curved parts, 19 and 20, and a catch-block, *r*. The steam-pipe *E* is connected to the valve-case *C*, and conveys the steam from the latter to the pipes in the 100 car. The yoke 8 is fitted onto the exterior of case *C*, and is connected to the arm *h'* and rod *i'*, as above described, whereby the receiving-connection is supported.

The said entering connection is secured to the end of the steam-pipe 6, the latter conveying steam from the pipes in the car to which it is attached by the coupling 5, and is made with an "expansion-joint," so called, consisting of the pipes H and I. The latter is screw-threaded for some distance on the end which screws into said coupling, and a stop-nut, K, and a set-nut, K', are placed thereon. 5 The end of pipe I within pipe H is provided with a collar having the usual packing, 4, therein. A stuffing-box, J, is secured to the end of pipe H, provided with the usual nut and packing, 4. By the nut K the movement 10 of the end of pipe H toward the latter is regulated, and when the cars move toward and from each other pipe I slides within pipe H, and thus any disturbance of the valve-connections by such movement is obviated. To 15 the end of pipe H which enters mouth A is secured the ball-joint case m^2 , having the ring o thereon, in which the ball-shaped end of the valve-case m is fitted and ground to make a steam-tight ball-joint, whereby a certain degree of lateral motion between the pipe H and the valve-case m is permitted to break the rigidity of the connection and let the parts work easy under the disturbing motion of the cars. The rings 3 and an elastic washer, 2, 20 are inserted in the case m^2 between the end of pipe H and the said ball-shaped part of case m , the said washer bearing against the ball and keeping the latter to its bearing in case m^2 . The valve-case m extends in tubular form 25 beyond said ball-shaped part thereof into the valve-case C, and has a plug screwed in its end provided with perforations 22 22 and a central valve-stem passage. A valve, d^2 , having a stem, d , is adapted to seat itself in the end of case m . The spindle d of valve d^2 has a head 30 outside of said plug, through which it passes, which serves to govern the movement of valve d^2 from its seat, and passes through a supporting cross-bar, 23, whereby the valve is supported in a central position, and is permitted, 35 with its stem, to have a motion back and forth in said case m .

The said entering connection of the valve parts just described is supported in the yoke 40 8, with which the arm h' is connected, as heretofore described, and through said yoke a rod, 9, passes, having one end secured to a tripping-ring, 7, on pipe H, and the other provided with a nut, 10, adjustable on rod 9. 45

The operation of my improvements is as follows: When, by the meeting of the cars, the entering and the receiving connections are brought to the positions shown in Figs. 1 and 2, spring B acts to engage the catch-block r 50 with the ring o, whereby the parts are held together, the movement of the car carrying the entering connection causing yoke 8 to move against the end of the arm 11 on ring 7 and

carry it under spring B. When the head of the valve-spindle d strikes valve D, the latter is driven away from its seat against the perforated disk f, and thereby spindle d and valve d^2 are moved in opposite directions, whereby valves d^2 and D are both moved away from their seats, letting steam flow in the direction indicated by the arrow in Fig. 2, directly through the valve-cases m and C into pipe E, and to the next car. When the cars are separated, the pipe H is drawn through its yoke 8 until the latter is brought against the nut 10, when ring 7 is drawn back, lifting spring B and disengaging catch r from ring o, letting the entering connections be drawn away from the receiving ones. The valve d^2 is then closed by steam-pressure, and the valve D by back steam-pressure from the car with which pipe E is connected. The packing-rings F serve to make the case m enter tightly into the part y, and prevent the steam from blowing backward. 70 75 80 85

The above-described devices by which the valve parts are hung to the cars permit of easy lateral and longitudinal motion of the valve-connections, whereby the latter accommodate themselves to the motions of the cars. 90

What I claim as my invention is—

1. In automatic steam-pipe couplings for railway-cars, a receiving-connection, substantially as described, having a wide mouth provided with a tubular extension having packing-rings within the latter, a back-pressure valve and valve-case connected with said extension, a spring connected with the latter provided with a catch-block and reverse curves and extending into a slot in said mouth, an entering connection, substantially as described, consisting of pipes H and I, the latter provided with the nut K, the ball-joint case m^2 , the valve-case m , valve d^2 , stem d , extending beyond the valve-case m , and means, substantially as described, for securing said connections to railway-cars, combined and operating substantially as set forth. 95 100 105

2. In combination, the mouth A, the tubes H and I, spring B, the case m^2 , having ring o thereon, the valve-case m , having a ball-joint connection with case m^2 and inclosing a valve, substantially as described, ring 7 and yoke 8, connected by rod 9, and means, substantially as described, for connecting said yoke with a car, all as set forth. 110 115

3. In combination, the rod 16, plate v, having the pivot-bolt 15, the yoke w, spring-bars 17, arm 15, having sleeve 14 thereon, the rod i^2 , arm h' , and yoke 8, substantially as set forth. 120

JAMES EMERSON.
